INVENTOR.

Edward H. Werner,
BY
Charles Turner Brown,
ATTORNEY.

UNITED STATES PATENT OFFICE.

EDWARD H. WERNER, OF CHICAGO, ILLINOIS.

INSULATOR.

Application filed December 12, 1921. Serial No. 521,915.

To all whom it may concern:

Be it known that I, EDWARD H. WERNER, a citizen of the United States, and a resident of Chicago, in the county of Cook and State 5 of Illinois, have invented certain new and useful Improvements in Insulators, of which the following, reference being had to the drawing accompanying and forming a part hereof, is a specification.

10 This invention relates to insulators for supporting safety rails in trackside installations of automatic train signal systems, and for supporting wires and other electric conductors.

15 Among the objects of the invention are to obtain an insulator which will arrest to a large extent, current leakage; an insulator adapted to support conductors having high potential currents; to obtain an insulator 20 provided with a lightning arrester, by means of which telegraph, telephone, and other lines will be protected from injury by lightning, and to obtain an insulator which will not be affected by moisture, rain, or water 25 precipitation from any source. Additional objects are to obtain an insulator which is economically made, durable, and not liable to get out of order, and to which broken or otherwise injured parts can be replaced 30 upon the removal of similar parts.

In the drawing referred to Fig. 1 is a top plan view of a construction embodying the invention.

Fig. 2 is a vertical section, on line 2—2 35 of Fig. 1, viewed as indicated by arrows; and

Fig. 3 is a side elevation, on a smaller scale than Figs. 1 and 2, with one of the elements of the device in a different position.

40 A reference character applied to designate a given part indicates said part throughout the several figures of the drawing, wherever the same appears.

A represents the base of the insulator, and

45 a, a, a, screws by means of which said base may be secured to a table or stand. B represents a screw threaded standard on base A, which is preferably integral with said base, and is so illustrated. C represents an

50 internally screw threaded sleeve which is adjustably mounted on standard B, by means of the corresponding screw threads illustrated. D represents an additional sleeve of insulating material, as glass, porcelain or other material, in which the

55 sleeve C is secured, and d represents an an-

nular groove at the upper end of sleeve D. E represents oil or other nonconducting liquid in groove d. F represents a screw threaded sleeve which is provided with annular flange f, which is also secured in sleeve D, in the upper end thereof. G represents a standard, which is provided with the annular flange g, and with screw threads below said flange corresponding with the screw threads in sleeve F. The upper end of the sleeve C and the lower end of sleeve F are provided with the inner annular flanges H, H'; and I, I' represent lightning arrester members which are 70 provided with annular flanges J, J'; said members being rigidly secured in determined relation by members K, K'. Said members I, I' are preferably made of carbon, and the sleeves C, F, in which they are secured 75 are of determined length so that when assembled in sleeve D the desired gap between said members I, I' is obtained, so that in case a current of high potential is conveyed to standard G, as a bolt of lightning, it may bridge said gap. L represents a water guard or shield, which is rigidly secured on standard G, between the insulating disks l, l'. To secure guard L in place the standard G is screwed into sleeve 80 F until the annular flange g is close to contact with the disk l', thereby forcing disk l' down on to flange f of sleeve F. M represents a safety, or ramp rail, which is illustrated as rigidly secured to member N, by 85 means of screws m, m; and member N is illustrated as rigidly secured to standard G by screws n, n.

To clean and replenish the groove d in sleeve D, said sleeve is turned on standard 90 B, substantially into the position illustrated in Fig. 3, in which position access can be easily had to said groove and its contents.

O represents a conductor from base A to ground P.

100 In case of any injury to parts A, B, C, D, F, G, I, I', or any of them, the base A may be removed from the table or stand on which it is mounted, by removing screws a, a, a; and thereafter the standard B 105 turned out of the sleeve C; after which the sleeve D may be turned and separated from standard. Thereafter, if necessary the members K, K' and members I, I', or either of them, may be removed and new members 110 substituted therefor. After the injured parts have been replaced by corresponding

new parts the several parts are re-assembled, and the base A again secured in place by screws *a*, *a*, *a*.

When the insulator is assembled as described and illustrated, in case any moisture collects under the guard L and falls upon the insulating sleeve D, the portion thereof which falls upon the oil E in groove *d*, will fall below the surface of said oil, and said oil, together with the upper end of sleeve D will retain the insulation of the insulator, and prevent leakage of current therethrough.

In case of a current of high potential, as a bolt of lightning is conducted to standard G, it will bridge the gap between members I, I' and flow through conductor O to ground P, without injury to the insulator.

In case the groove *g* contains no oil and moisture precipitates therein, the sides of said groove rapidly become dehydrated, and thereafter no leakage of current will occur over the upper end of sleeve G.

I claim:

25 1. In an insulator, a base provided with a screw threaded standard, a sleeve of insulating material mounted on said standard, said

sleeve provided with an annular groove at the upper end thereof adapted to receive and retain oil, a standard mounted in said last named sleeve, and a guard rigidly mounted on said last standard between disks of insulating material, all combined as set forth.

2. In an insulator, a base, a standard on said base, and a sleeve mounted on said standard, in combination with an additional sleeve of insulating material provided with an annular groove on the upper end thereof adapted to receive and retain oil, and rigidly mounted on said first sleeve, a sleeve rigidly secured in the upper end of said additional sleeve, lightning arrester members secured in spaced relation in said first and last named sleeves, an additional standard secured in said last named sleeve and a water guard secured on said last standard and separated therefrom by disks of insulating material.

EDWARD H. WERNER.
